UNITED STATES PATENT OFFICE.

FREDERICK SCHMIDT, OF DALTON, PENNSYLVANIA, ASSIGNOR OF ONE-HALF TO
ALEXANDER P. BOTSCHELLER, OF DALTON, PENNSYLVANIA.

HORSESHOE-CALK.

1,156,713.

Specification of Letters Patent. Patented Oct. 12, 1915.

Application filed January 23, 1915. Serial No. 3,993.

To all whom it may concern:

Be it known that I, FREDERICK SCHMIDT, citizen of the United States, residing at Dalton, in the county of Lackawanna and State of Pennsylvania, have invented new and useful Improvements in Horseshoe-Calks, of which the following is a specification.

My present invention pertains to horse-shoes and horseshoe calks.

10 It consists, first—in the combination with a horseshoe body, of peculiar and advantageous calks so arranged as to afford a solid footing for a horse, and so as to assure the front and back calks assuming positions 15 perpendicular to the pavement or roadway when the horse is in motion, this with a view to enabling the calks to readily penetrate snow or ice or a slippery pavement without material wear of the calks, and, 20 second—in calks so constructed that they are adapted to be securely socketed in a shoe body without injury to the calks by the hammer blows, and also adapted to prevent a horse slipping sidewise as well as in forward 25 and backward directions and yet are not liable to be filled with snow or ice.

Other advantageous characteristics of the invention will be fully understood from the following description and claims when the 30 same are read in connection with the drawings, accompanying and forming part of this specification, in which:

Figure 1 is an inverted plan view of a horseshoe constructed in accordance with my 35 invention. Fig. 2 is a side elevation of the shoe, with a portion of the shoe body in section. Fig. 3 is a detail vertical section illustrating the manner in which the shanks of the calks are socketed in the shoe body. 40 Fig. 4 is a detail perspective of a modified calk hereinafter specifically referred to.

Referring by numeral to the said drawings, and more particularly to Figs. 1 to 3 thereof: 1 is the shoe body, and 2—2 are 45 the calks; the shoe body being formed of wrought iron, and the calks being made in any approved manner of steel or any other hard material compatible with their purpose.

50 In accordance with my invention, the shoe body is provided with four (more or less) upwardly-tapered sockets 3 which extend vertically through the body from the underside to the upperside thereof.

55 By reference to Figs. 1 and 2, it will be

noticed that the convex sides of the forward calks are foremost, and the convex sides of the rear calks are rearmost. It will also be noticed that the concavo-convex portions of the forward calks are inclined downwardly 60 and forwardly from the vertical while the concavo-convex portions of the rear calks are inclined downwardly and rearwardly from the vertical. Otherwise the calks are identical in construction and therefore a detailed description of the calk shown in Fig. 3 will suffice to impart a definite understanding of all. The calk referred to is made in one piece, and comprises an upwardly tapered shank 4, having, by preference, an 65 upright fin or feather 5 on its side, an enlargement 6 arranged at the lower end of the shank and at right angles thereto and having an underside 7 also disposed at right angles to the shank, and the portion 8, of 70 concavo-convex form in cross-section, carried by and depending from the enlargement 6, and having a lower beveled end 9. Being open at one side it will be manifest that the portion 8, is not liable to be filled 75 with and to have its efficiency impaired by snow or ice. It will also be manifest that the sides of the said portion 8 will preclude sidewise or lateral slipping of the calk on a slippery pavement, while the front part of 85 the concavo-convex portion will effectually prevent slipping of the calk forwardly or rearwardly. I would also have it understood at this point that by reason of the calks having the concavo-convex portions, 90 arranged in inclined positions from the vertical, as best shown in Fig. 2, the intermediate parts of the lower ends of the calks will first engage the ground or pavement when the horse is in motion. This is advantageous 95 inasmuch as the said intermediate parts of the lower ends will first penetrate the roadway or the snow or ice thereon, and in that way will assure the horse gaining a secure foot hold without unnecessary wear of the 100 lower ends of the calks. It will further be noticed that by reason of the inclination of the concavo-convex portions of the calks from the vertical, the calks will rest perpendicular to the pavement or roadway when 105 the shoe body is inclined with respect to the surface of the pavement or roadway. Because of this, the calks are certain to be imbedded in the surface of the roadway and will not slip idly over said surface as would 110

be the case were said portions of the calks arranged perpendicular or at right angles to the shoe body.

Manifestly when the shanks 4 equipped with fins or feathers 5 are driven into the tapered sockets 3 of the shoe body, the said fins or feathers will cut ways in the walls of the sockets 3 and will thereby effectually prevent the calks turning about their axes in the body.

An important advantage peculiar to my novel calks resides in the disposition of the undersides 7 of the enlargements 6 at right angles to the vertical-centers of the calk shanks. The said arrangement of the undersides 7 is of advantage because when it is desired to drive a calk into its complementary socket in the shoe body a punch can be arranged with its inner end against the underside 7 of the enlargement 6 of the calk, and hammer blows can be imposed on the outer end of the punch to drive the calk shank home, or if preferred the blows of a thin hammer head can be imposed directly against the said underside 7. When this is done it will be observed that breaking down of or any other injury to the sharpened end 9 of the concavo-convex portion 8 of the calk is precluded, which is an important advantage.

When the shanks of the calks are fully socketed in the shoe body 1, it will be noticed that the calk enlargements 6 are spaced from the underside of the body 1. This is advantageous since it permits of a wedging instrument being driven between the enlargements 6 and the underside of the shoe body to withdraw the calk shanks from the sockets in the body.

The modified calk 2^a shown in Fig. 4 is similar in construction to the calks shown in Figs. 1 to 3, in all respects with the exception that the concavo-convex portion 8^a of the modification is made angular instead of curvilinear. It is to be noted however that the modified calk is possessed of all of the practical advantages hereinbefore ascribed to the calks illustrated in Figs. 1 to 3.

It will be gathered from the foregoing that notwithstanding their practical advantages, my novel calks are susceptible of be-

ing cheaply produced and are adapted to be expeditiously and easily secured by frictional contact in a shoe body, without the employment of skilled labor, and that when occasion demands any one of the calks can be as readily removed from the shoe body. There is however, no liability of the calks becoming loose or being lost incidental to the use of the shoe equipped with the calks.

It is obvious that when desired the sockets 3 and the shanks 4 may be inclined conformably with the calk portions 8, without involving departure from the scope of my claims.

Having described my invention, what I claim and desire to secure by Letters-Patent, is:

1. In a horseshoe, a shoe body, and forward and rear calks fixed to and depending from the body and having lower portions of concavo-convex form in cross-section terminating in square and beveled lower ends; the convex sides of the forward calks being arranged foremost, and the convex sides of the rear calks being arranged rearmost, and the concavo-convex portions of the forward calks being inclined downwardly and forwardly from the vertical, and the concavo-convex portions of the rear calks being inclined downwardly and rearwardly from the vertical.

2. As a new article of manufacture, a one-piece horseshoe calk comprising an upwardly-tapered vertical shank, an enlargement at the lower end of the shank and adapted to be spaced from the underside of a shoe body, said enlargement having an underside flat and unobstructed and disposed throughout its area at right angles to the vertical center of the shank, and a portion, of concavo-convex form in cross-section, depending from the said enlargement and inclined from the vertical.

In testimony whereof I have hereunto set my hand in presence of two subscribing witnesses.

FREDERICK SCHMIDT.
